CLAIM

The ornamental design for a tripod leg, as shown and described.

DESCRIPTION

FIG. 1 is a front elevational view of a tripod leg showing my new design;

FIG. 2 is a top plan view thereof;

FIG. 3 is a bottom plan view thereof;

FIG. 4 is a left side view thereof;

FIG. 5 is a right side view thereof;

FIG. 6 is a rear elevational view thereof;

FIG. 7 is a sectional view taken along line 7-7 of FIG. 1;

FIG. 8 is a sectional view taken along line 8-8 of FIG. 1;

FIG. 9 is a sectional view taken along line 9-9 of FIG. 1; and,

FIG. 10 is a sectional view taken along line 10-10 of FIG. 1.

The holes in the base plate and middle support assembly for the tripod leg are shown in broken lines to depict portions of the tripod leg that form no part of the claimed design.
